HOLDER FOR A PAIR OF SPECTACLES

Lynn V. Adams, Raleigh, N. C.

Application March 10, 1955, Serial No. 34,988

Term of patent 7 years

(Cl. D57—1)

I claim:

The ornamental design for a holder for a pair of spectacles, as shown.
